TOY GUN

Claud A. Davis, Wauseon, Ohio, assignor, by
mesne assignments, to Gladys Lemon, Fulton
County, Ohio

Application February 19, 1949, Serial No. 77,402

1 Claim. (Cl. 124—21)

1

This invention relates to an impelling tool of the recoil-release type of toy gun or pistol.

This invention has utility when embodied in a rigid wire frame embodying a revolver grip portion with an extension therefrom in lieu of a barrel. An elastic element of the rubber band characteristics may be placed under tension to hold a rod, as guided by the extension, retracted, which element, upon trigger release, quickly thrusts the rod to the limit determined by the extension. Herein there is shown a tip for the outward end of the rod, which may form a pocket for a projectile. Furthermore, with such tip in the form of a readily collapsible fine wire spiral cone, there is a ventilated impingement area effective as an insect destroyer, more particularly as to household pests such as mosquitoes and flies.

Referring to the drawings:

Fig. 1 is a side elevation of an embodiment of the invention in a toy gun, the dotted lines showing the projected position of the rod for impingement to slaughter a fly;

Fig. 2 is a view from the left of Fig. 1, looking into the wire spiral tip for the impelling rod;

Fig. 3 is a side view of the tip of Fig. 2, with a dotted line showing of a projectile therein to be thrown or released;

Fig. 4 is a detail view of the trigger pivot and adjacent wire frame of the gun, with the trigger and its spring catch in dotted lines at the released position therefor;

Fig. 5 is a section on the line V—V, Fig. 1, showing the extension end guide for the impeller rod;

Fig. 6 is a section on the line VI—VI, Fig. 5, showing a plan view of the impeller rod guide;

Fig. 7 is a view from the line VII—VII, Fig. 1, of the slide actuator for the impeller rod;

Fig. 8 is a side elevation of the slide from the right of Fig. 7;

Fig. 9 is a detail view in side elevation, at cocked or set position with the dotted line showing its mounting and the torsion spring holder therefor; and

Fig. 10 is a perspective view of the trigger carried torsion spring of .041" diameter.

The grip and extension are herein shown as of one piece of plated #12 gage iron wire having an end portion 1, aft from which is a grip skeleton or outlining frame portion 2 having a top riser portion 3 at right angles to the end portion 1. From the tip of the portion 3 there is a straight slide guide portion 4 to an offset drop end 5 with a straight return portion 6, parallel

5 to the portion 4. The portion 6 has an abrupt trigger catch minor offset 7 past which offset 7 the portion 6 extends to a right angle end portion 8 having weld anchoring means 9 with the portion 3 thereby to form a closed figure portion for the extension. More remote from the portion 8 than the trigger catch 7 additional anchoring means 9 connect the wire frame end portion 1 with the portion 6, forming at the grip frame a 10 second closed figure portion.

At the offset 5 is a rigid thin sheet metal guide of stock of approximately .020" thickness. Anchoring means 9 attaches U-end portion 10 of the guide at the offset 5 with a cone-stiffened central portion or guide 11 approximating mid-position and in a common plane as to its axis with the parallel slide guide portions 4, 6. With the outer flare edge of the conical guide 11 to some extent against the side of the offset 5 remote from the grip 2, there is integral with the cone 11 a hook 12 ending in a return-bend end 13.

20 A pair of sheet metal plates 14, of about the gage of the guide 10, 11, 12, 13, have weld anchorage 9 assembling therewith as a unit legs 15 of an offset return bend rigid fine wire 16 of a U-element. The parallel ends of the plates 14 are outwardly offset to form parallel troughs 17 as slide shoes to ride upon the extension parallel wire portions 4, 6.

25 Medially of the plates 14 and having anchoring means 9 effecting further rigid assembly of this slide unit and fixing therewith is a rod 18. About the rod 18, say of similar gage to the rod wire of the one-piece grip and extension, is a fine (.018" diameter) wire helical spring as a buffer or cushion 19 to abut the slide 14. The wires 4, 6, may be medially flexed sufficiently to insert the slide 14 for the channels or troughs 17 to 30 contact in positioning the rod 18 approximately midway between the portions 4, 6, and parallel thereto in the extent of the rod 18 thru the guide 11.

35 Upon the free end or protruding portion of the rod 18 as beyond the guide cone 11, a fine wire has a closely wound helical base portion 20. This 40 is a spring having an initial set somewhat less in internal diameter than the outside of the rod 18. From this helix 20 and integral therewith is a spiral cone 21 forming a holder or readily collapsible tip for the impeller rod 18. The helix 50 20 is turned upon the end of the rod 18 in forming a rigid assembly.

The grip 2 spaced from the wire frame portion 1, has attached thereon, by weld anchoring 9, a sheet metal clip 22 fixing a pivot bearing 23, with which may coact an eyelet 24 in rock-

ably mounting a trigger 25 to hang in proximity to the grip 2. The trigger 25 has an upper offset 26 of parallel cheeks adapted to ride astride the grip frame 2 adjacent the end portion 1. One of these cheeks 25 has a pair of parallel cuts 27 to permit out-bending of an intermediate portion 28 of the cheek 25 as an anchoring port.

Insertable in the port 28 is a diametrical end portion 29 of a torsion spring coil 30. From this coil 30 as assembled with the trigger 25, 26, extends an arm 31 with an angular offset free end 32 adapted to project under the wire portion 6.

Actuating means for the impeller rod 18 is herein disclosed as an endless rubber band 33 having one end looped about the U-bend 16 fixed with the slide 14. The band 33 is then stretched therefrom to be tension caught in the hook 12 at the region of the fixed guide 11. A practical range of elasticity for the band 33 is that at about four times its unstretched length the slide 14 may be at the side of the offset 7 remote from the guide 11. In the riding of the slide 14 to this position, the band 33 is brought to its full tension, and the torsion spring coil 30 keeps its offset 32 urged toward the underside of the wire portion 6. At the position where the slide U-wire bend 16 is slightly short of the wire end 8, the slide 14 has traveled theretoward past the offset 7, and the wire offset 32 carried by the trigger 25, 26, lodges between the lower channel portion 17 of the slide 14 and the offset 7. Considering the tool as a gun, the trigger is now cocked and the impeller rod 18 is thus locked in its recoil position. The child player, or the gun operator, by grasping the grip portion 2, may have his index or trigger finger in proximity to the trigger 25. Upon pulling the trigger 25, the torsion wire wire offset 32 which holds the trigger, rides upon the lower side of the offset 7. At once, the slide 14 is thus cleared of obstruction, and the band 33 quickly throws the slide forwardly with the bumper cushion 19 striking the cone 11, with the rod 18 having ridden there thru and carrying the tip holder 21, say to throw at a target or mark a ball 35, or to have the coil spiral 21 impinge a curtain or wall 36 and kill a fly 37.

What is claimed and it is desired to secure by Letters Patent is:

A gun comprising in a common plane a one-piece wire handle grip with a pair of slide guides 5 therefrom to a region remote from the grip, a projectile directing guide spanning between the slide guides at said region, a projectile rod protruding through the directing guide, a slide fixed with and carried by the rod and having opposite- 10 ly directed U-shaped seats adapted to slide along the opposing portions of the pair of slide guides in locating the rod co-planar with the one-piece wire grip and said slide guides, one of said slide guides in proximity to the grip having a cam bend therein, tension means coacting between the rod and directing guide to project said rod forwardly, and trigger means pivotally mounted to said grip normally engaging said slide guide rearwardly of said bend and engaging one of 15 said U-shaped seats when the rod is in retracted position, said bend being adapted to cam said trigger means from said one of said U-shaped seats to disengage the same to free said rod for forward projection.
